TRAVELING WAVE TUBE HAVING RECTANGULAR WAVEGUIDE SLOW WAVE STRUCTURE WITH EQUIANGULARLY SPACED ELECTRON GUNS

Joseph E. Rowe, Ann Arbor, Mich., assignor to the United States of America as represented by the Secretary of the Air Force

Filed May 19, 1961, Ser. No. 111,411
1 Claim. (Cl. 315—3.6)

This invention relates to traveling wave tubes of the type employing an open sided helical rectangular waveguide as a slow wave structure and has as its object an increase in the efficiency and power capabilities of such tubes. In prior art devices of this type the dimension of the waveguide in the radial direction is less than the outer radius, leaving space to pass the electron beam of the tube along the axis of the helix. This construction inherently limits the coupling between the beam and the electromagnetic wave in the waveguide with the result that the full power and gain capabilities of this type of tube are not realized.

In accordance with the invention the radial dimension of the helical waveguide is made equal to the outer radius of the helix and the electron beam is displaced from the axis of the helix and allowed to pass through aligned apertures in the walls of the waveguide. This permits a greater interaction between the beam and the electromagnetic wave in the slow wave structure and results in increased amplification and power output. Further, this construction permits a plurality of beams to be used with a further improvement in the gain and power capabilities of the tube.

A more detailed description of the invention will be given with reference to the specific embodiment thereof shown in the accompanying drawing in which—

FIG. 1 is a cross sectional view of the tube, and

FIG. 2 shows an alternative means for coupling to the slow wave structure of the tube.

Referring to FIG. 1, the tube comprises an evacuated cylindrical metal envelope 1 within which is located a slow wave structure in the form of a helical rectangular waveguide with the inner side open. This waveguide is formed by a metallic helical ribbon 2 having one edge in continuous electrical contact with the inner surface of cylinder 1. The width of the ribbon is made equal to the inner radius of the cylinder so that the waveguide wall in the radial direction extends to the axis of cylinder 1. An input coupling 3 is provided for introducing radio frequency energy into the slow wave structure and an output coupling 4 for removing amplified radio frequency energy from the tube. These couplings are illustrated as loops but any suitable coupling device may be used. An alternative form is shown in FIG. 2 where the coupling device is a rectangular waveguide 3' formed as an extension of the helical waveguide of the tube 1'.

In the tube illustrated there are four electron beams provided by four similar electron guns spaced 90° apart, three of which are shown in the figure. These guns may be of any suitable type. In the example shown the outer shell 5, having a beam aperture 6, serves as the accelerating electrode of the gun and is supported from conductive ring 7 by means of a conductive bracket 8. The remainder of the gun, not shown, is insulatedly supported inside shell 5 and comprises the cathode and focusing electrodes. Conductor 9 connects the cathode through sealing and insulating bead 10 to the negative terminal of direct current source 11. Conductors 12 passing through

2

sealing and insulating beads 13 carry heater current from source 14 to the cathode heater. The body 1 of the tube is connected through electron collectors 15, one for each beam, and conductor 16 to the positive terminal of source 11. Since accelerating electrode 5 is at the same potential as the body 1, it is positive relative to the cathode of the gun by the amount of the voltage of source 11. This voltage is made such as to give the required electron velocity. Each beam passes through a series of aligned apertures 17 in the ribbon 2 to its collector 15.

The operation of the device depends, as in other traveling wave tubes, on the conversion of the kinetic energy which the electrons have by virtue of their velocity into electromagnetic energy in the helical waveguide slow wave structure. The electron beams leave the electron guns to the left of the input to the slow wave structure essentially unmodulated and enter the slow wave structure at the same end at which the radio frequency energy is introduced through the input coupling device 3. The axial component of the electric field exerts a force on the electrons in the beam, accelerating some and decelerating others, to produce a bunched beam. The bunched beam induces currents in the slow wave structure and, because the slow wave structure has impedance, a voltage is developed which adds to the amplitude of the voltage already on the helix, resulting in an amplification of the impressed radio frequency wave. The amplified wave is taken from output coupling device 4.

In order for the radio frequency wave and the electron beam to interact the velocity of the electrons must be slightly greater than the axial phase velocity of the wave on the slow wave structure. As the electrons travel down the length of the slow wave structure they gradually slow down due to the conversion of their kinetic energy into electromagnetic energy. Therefore, it is desirable that the axial phase velocity of the electromagnetic wave in the helical waveguide be decreased at the same rate that the velocity of the electrons decrease in order to obtain the optimum relationship between wave velocity and electron velocity over the length of the slow wave structure. Since the axial phase velocity is directly related to the pitch of the helix of the waveguide, this may be accomplished by gradually decreasing the pitch of the helical waveguide in approximately an exponential manner along the length of the tube as shown in FIG. 1.

I claim:

A traveling wave tube comprising an evacuated metallic cylinder, a conductive helical ribbon having one edge in continuous electrical contact with the inner surface of said cylinder and having a width equal to the inner radius of said cylinder, said ribbon forming with the inner surface of said cylinder a helical waveguide slow wave structure, said ribbon having aligned apertures therein to form axially directed passageways, the axes of said passageways being parallel to and equally spaced from the axis of said cylinder and having equiangular spacing about the axis of said cylinder, means for passing a beam of electrons through each passageway, means for introducing high frequency energy into said slow wave structure at the end at which the electrons enter said passageways, and means for removing amplified high frequency energy from said slow wave structure at its other end.
